(57) **CLAIM**

The ornamental design for a glassware polishing system, as shown and described.

DESCRIPTION

FIG. 1 is a top, front, right perspective view showing our new design for a glassware polishing system;

FIG. 2 is a top plan view thereof;

FIG. 3 is a left side elevation view thereof;

FIG. 4 is a right side elevation view thereof;

FIG. 5 is a bottom plan view thereof;

FIG. 6 is a front elevation view of thereof;

FIG. 7 is a top, rear, left perspective view thereof; and,

FIG. 8 is a rear elevation view thereof.

The broken lines showing portions of the glassware polishing system are for illustrative purposes only and form no part of the claimed design.
